UNITED STATES PATENT OFFICE

CHARLES G. BAUER, OF BROOKLYN, NEW YORK, ASSIGNOR TO JULIUS KAPLAN, OF BROOKLYN, NEW YORK

GARMENT HANGER

Application filed January 16, 1930. Serial No. 421,134.

My invention relates to garment hangers, and further relates to holders for moth balls and other holders.

One of the objects of my invention is to provide devices of this character which may be cheaply made of sheet metal, are of rigid, strong and durable construction, and attractive in appearance.

Another object of the invention is to provide a garment hanger in which there is provision of novel and improved means for retaining moth balls and other disinfectants.

Another object of the invention is to provide a novel and improved holder construction which may be cheaply made of a single piece of sheet metal.

A further object of the invention is to provide a novel and improved collapsible garment hanger.

20 The several features of the invention, whereby the above-mentioned and other objects may be attained, will be readily understood from the following description and accompanying drawings, in which:

25 Figure 1 is a side view, partly in section, of a garment hanger embodying certain features of my invention in their preferred form;

Fig. 2 is a detail side view on an enlarged scale of the central portion of the hanger;

Fig. 3 is a sectional view taken on the line 3—3 of Fig. 1;

Fig. 4 is a sectional view taken substantially on the line 4—4 of Fig. 1;

Fig. 5 is a transverse sectional view taken on the line 5—5 of Fig. 1;

Fig. 6 is a front view of a holder for moth balls and similar articles embodying certain features of my invention in their preferred form;

Fig. 7 is a transverse sectional view taken on the line 7—7 of Fig. 6;

Fig. 8 is a side view of my improved collapsible garment hanger, shown in full lines in open position and in broken lines in closed or folded position;

Fig. 9 is a detail sectional view taken on the line 9—9 of Fig. 8; and

Fig. 10 is a sectional plan view of the cen-

tral portion of the hanger illustrated in Fig. 8.

The garment hanger illustrated in Figs. 1 to 5, inclusive, of the drawings may have its two supporting arms 2 made of a single piece of sheet metal, with the greater portion of each arm bent into substantially inverted U-form in cross section. At the junction of the two arms, their sides are crimped inwardly to provide inwardly projecting lugs 4, the inner ends of which may abut each other. The arms are inclined downwardly from the central portion of the hanger. A hook 6 has its shank extended through a central aperture in the hanger with its end hooked over the abutting end portions of the lugs 4.

A substantial portion of the length of each arm of the hanger between the ends thereof, is provided with downwardly struck transverse strip portions 8 that are spaced apart. 70 These strip portions 8 and the upwardly projecting strip portions 10 which are formed by striking down the portions 8, may be substantially semi-cylindrical in form, and together provide an elongated substantially cylindrical holder in the form of a cage in which moth balls or other disinfectant 12 may be placed. The moth balls may be inserted in the upper end of the cage, the lower outer end of the cage having one or more of the transverse strips 8 shortened so as to contract this end of the cage and thus retain the balls therein. The upper end of the cage may be closed by a clip 14 which may be detachably inserted between two of the strips 8. 75 80

With this construction, it will be apparent that my improved garment hanger as illustrated in Fig. 1 of the drawings may be cheaply made of a single piece of sheet metal, is of rigid, strong and durable construction, and attractive in appearance. The skeleton holders or cages formed by the transverse strips 8 and 10, provide convenient holders for moth balls and may be formed without adding materially to the expense of manufacture of the hanger as a whole. 85 90

The holder for moth balls illustrated in Figs. 6 and 7 of the drawings, may be made of a single elongated piece of sheet metal having its longitudinal edges 16 bent over 100

to add to the rigidity thereof, and having a suitable apertured upper end 18 whereby the holder may be conveniently suspended. The moth ball holding portion of the holder is 5 formed by alternatively downwardly struck and upwardly struck transverse strip portions 20 and 22, respectively, which may be of substantially semi-cylindrical form. The holder above the strip portions 20 and 22, 10 may be provided with an opening 24 so as to permit the moth balls to be inserted into the upper end of the holder. The balls are retained at the lower end of the cage by the lower end of the body portion of the holder 15 which extends across said end of the cage.

The collapsible garment hanger illustrated in Figs. 8, 9 and 10 is provided with two arms 26, each of which may be made of a single piece of sheet metal bent into substantially inverted U-form in cross section for a substantial portion of the length thereof. The inner end portions 28 of the sides of each arm are brought into close proximity as shown. Plates 30 arranged side by side are positioned 20 between said side portions 28 of the inner ends of the two arms 26. The arms are pivoted to the supporting plates by means of rivets 32, the parts of the side portions 28 surrounding the rivet holes therein being 25 countersunk or pressed inwardly so as to provide suitable pivot bearings for the arms. A hook 34 has its shank extended downwardly between the plates 30, the plates being centrally bent around to provide an aperture for 30 receiving the shank. The lower end of the hook shank is bent or hooked over a horizontal flange 36 on the lower edge of one of the plates 30. The other plate 30 is provided with a corresponding flange 36 and the ends of 35 these two flanges, when the hanger is in usable position, provide supporting abutments for the under sides of the arms 26 of the hanger to hold the arms in position. To collapse or 40 fold up the hanger, it is merely necessary to swing the arms upwardly about the pivots 32, whereby the hanger may be conveniently carried in a traveling bag or other container.

As will be evident to those skilled in the art, my invention permits various modifications without departing from the spirit 50 thereof or the scope of the appended claims.

What I claim is:

1. A garment hanger of the class described having one of its arms made of sheet metal 55 having alternately arranged and spaced upwardly extending and downwardly extending transverse strip portions providing a cage adapted to receive moth balls.

2. A holder for moth balls comprising a 60 piece of sheet metal having alternately arranged and spaced struck-up and struck-down transverse strip portions providing an elongated cage adapted to receive moth balls, the moth balls being inserted in one end of 65 the cage and the opening at the other end of

the cage being of less area than the diameter of the balls.

3. A garment hanger of the class described having one of its arms made of sheet metal bent into substantially inverted U-form in cross section having a plurality of downwardly struck transverse strip portions spaced apart and together with the upwardly projecting strip portions formed thereby providing a cage adapted to receive moth balls. 75

4. A garment hanger of the class described having one of its arms made of sheet metal of substantially inverted U-form in cross section and having downwardly struck spaced strip portions which together with the upwardly extending transverse strip portions formed thereby provide a cage adapted to receive moth balls, the downwardly struck strip portions at one end of said cage being shorter than the others to close said end to 80 the moth balls, and a clip adapted to be inserted between at least two of said downwardly struck strip portions for closing the other end of the cage to the moth balls. 85

5. A garment hanger of the class described comprising a single piece of sheet metal formed to provide outwardly projecting arms of substantially inverted U-form in cross section with the central portion of the sides of said piece crimped inwardly and the two arm portions bent downwardly at an angle from the center of the piece, and a hook member having its shank extending through a central aperture in said piece and hooked over the inner ends of said inwardly crimped portions. 95

6. A garment hanger of the class described comprising two members of sheet metal forming the arms of the hanger substantially inverted U-form in cross section for a substantial portion of the length thereof with the inner end portions of their sides brought substantially together, two plates arranged side by side and inserted between the inner end portions of the sides of said arms, rivets pivotally connecting the inner ends of said arms to said plates, and a hooked member having its shank extending between said plates with the adjacent portions of the plates bent to provide an aperture for said shank, whereby 105 the arms may be swung upwardly about said pivot rivets. 110

In testimony whereof, I have signed my name to this specification.

CHARLES G. BAUER.
